UNITED STATES PATENT OFFICE.

HERMAN O. STUBBS, OF NEWARK, OHIO.

SHOESTRING-FASTENER.

SPECIFICATION forming part of Letters Patent No. 777,563, dated December 13, 1904.

Application filed August 17, 1904. Serial No. 221,057. (No model.)

To all whom it may concern:

Be it known that I, HERMAN O. STUBBS, a citizen of the United States of America, residing at Newark, in the county of Licking and State of Ohio, have invented certain new and useful Improvements in Shoestring-Fasteners, of which the following is a specification, reference being had therein to the accompanying drawings.

10 This invention has relation to certain new and useful improvements in shoestring-fasteners, and has for its object the provision of novel means in connection with the ordinary shoe-fastener whereby the laces after they 15 have been placed in engagement with the ordinary fastener carried by the upper of the shoe can be secured, whereby the laces cannot become loose from the upper of the shoe.

Another object of this invention is to provide 20 a novel form of a lace-fastener which is adapted to be secured above the ordinary fasteners commonly used, whether the same be hooks or eyelets, and in constructing my improved lace-fastener I have employed as simple 25 a construction as possible, whereby the expense of manufacture will be reduced to a minimum, at the same time presenting a construction which will be strong and durable and retain the laces of the shoe when they are 30 once placed therein.

Briefly described, my improved fastener comprises two cylindrical members which are adapted to be secured upon each side of the upper, preferably near the top thereof and 35 above the ordinary fasteners, these cylindrical members carrying hooks formed of wire whereby when the shoe has been laced the laces may be passed through the cylindrical members, tied together, and then secured 40 in the hooked portions of the members.

The above construction will be hereinafter more fully described and then specifically pointed out in the claims, and, referring to the drawings accompanying this application, Figure 1 is a fragmentary view of the top of an upper of a shoe, showing my improved fastener secured thereto. Fig. 2 is a top plan view of my improved fastener, showing the 45 same secured to a portion of the upper of a

shoe. Fig. 3 is a vertical sectional view of the cylindrical member of my improved fastener. Fig. 4 is a detail perspective view of one of the wire hook members. Fig. 5 is a vertical sectional view of the cylindrical member of my improved fastener, showing the manner of securing the same to the upper of a shoe. 55

Throughout the several views of the drawings similar reference characters designate 60 corresponding parts, and the reference character A designates the upper of the shoe, which upon its sides is provided with the ordinary clasps or hooks B, and the laces C and D are secured in these hooks or clasps in the ordinary manner, as illustrated in Fig. 1 of the drawings. 65

My invention resides in the fastening of the upper end of the shoe-laces, whereby when the shoe has once been laced it will be impossible for the same to become loose or untied, and in carrying my idea into effect I have provided two cylindrical members 1 and 2, these members being identical in construction and are placed upon the sides of the upper 70 of the shoe. The cylindrical members 1 and 2 have their ends flanged, as designated at 3 3, the object of which will be hereinafter more fully described. In order to secure these cylindrical members upon the sides of the upper 75 of the shoe, I employ a metallic strip 4, which passes through the cylindrical member and has its ends bent rearwardly, as designated at 5, and passed through the upper A of the shoe, the ends of the metallic strip being bent 80 downwardly, as designated at 6 6, whereby the cylindrical member will be firmly secured to the upper A of the shoe. The hook portion of my improved fastener comprises a piece of wire which is bent to form a loop 7, 85 each end of the wire being bent upon itself, as indicated at 8, whereby the loop 7 will form 90 a hook. The ends of the wire are then bent around the cylindrical member 1, as designated at 9 9, the wire passing under the flanges 95 3 3, and each flange is sheared to permit the loose end of the wire to extend outwardly, as designated at 10 10, and this loose end of the wire is bent upon itself, as indicated at 11 11, to engage each side of the upper, as shown in 100

Fig. 2 of the drawings. It will be seen by this construction that the cylindrical members are supported by each side of the upper A of the shoe and that the flanges 3 3 of the cylindrical members support the loop portion 7 and that an outward movement of said loop portion will be prevented by the loose ends 11 of the wire engaging behind the upper of the shoe. After the laces have been passed 10 around the clasps or hooks B in the ordinary manner the ends of the laces are passed upwardly through the cylindrical members 1 2, and the ends of the laces are then tied into a suitable knot or bow, and to prevent this bow 15 or knot from becoming loose I preferably place one end of the string in each of the hook portions 7 7, and after the same is tied in a bow I place one of the bows and the end of the string in one of the hooks 7 upon one side 20 of the upper and the other bow and end in the hook 7 carried upon the opposite side of the upper. By so securing the ends of the string it will be impossible for the same to become disengaged from the shoe until it is 25 desired to remove the same, at which time the ends of the laces or string may be readily withdrawn from the hook members, the bow untied, and the ends of the string withdrawn from the cylindrical members 1 2, whereby 30 the shoe may be unlaced.

It will be observed from Fig. 1 of the drawings that my improved lace-fastener is compact in form and presents a neat appearance in conjunction with the ordinary fasteners, 35 and while I have herein shown the fastener as being particularly adapted for shoe-laces it is obvious that the same may be readily employed upon such articles or garments wherein laces are used and that the ends of said laces

may be readily secured together in the manner 40 heretofore described. I do not care to confine myself to the specific shape or manner of bending the wire forming the hook portions 7, but may so construct the same in any desired manner whereby the results above stated 45 will be accomplished, and I may make various other slight changes in the details of construction without departing from the general spirit of the invention.

Having fully described my invention, what 50 I claim, and desire to secure by Letters Patent, is—

1. In combination with an upper of a shoe, a hollow cylindrical member secured upon each side of the upper, with its bore parallel 55 to the surface of the upper, said cylindrical member having its ends flanged, a wire bent to form a hook and secured under said flanges, a metallic strip passing through said cylindrical member and engaging the upper of the 60 shoe, substantially as described.

2. The combination with a shoe, of string-fasteners each composed of a hollow cylindrical member secured to the shoe with its bore parallel to the surface thereof and adapted 65 to receive a shoestring, a staple passing through the bore of the said member and securing it in position on the shoe, a wire hook mounted on said member and also adapted to receive the shoestring, substantially as de- 70 scribed.

In testimony whereof I affix my signature in the presence of two witnesses.

HERMAN O. STUBBS.
